UNITED STATES PATENT OFFICE.

WALTER H. COTTON, OF CHICAGO, ILLINOIS.

PRESS.

Application filed December 1, 1922. Serial No. 604,259.

To all whom it may concern:

Be it known that I, WALTER H. COTTON, a citizen of the United States, and resident of Chicago, county of Cook, and State of Illinois, have invented certain new and useful Improvements in Presses, of which the following is a specification, and which are illustrated in the accompanying drawings, forming a part thereof.

10 The invention relates to machines for pressing material into various shapes and particularly to mechanical presses for the forming of fire clays.

15 The objects of the invention are to provide a press adapted to automatically form a brick of very large size which require a great quantity of clay at each charge: it being important in a press of this type that an abundance of space be provided for the 20 charging mechanism the conveyance of clay to the machine, etc., a further object is to provide a press in which the principal working parts may be protected from floating dust and grit that is very prevalent upon 25 the delivery floors of press rooms.

In pressing brick of great thickness, using clay low in moisture it is a difficult task to form the brick with hard centers owing to the friction due to the low viscosity of the 30 clay and also to the friction of the clay on the side walls of the mold. It is therefore an object of this invention to provide mechanism for overcoming this difficulty without the use of extreme moisture in the clay 35 which results in the loss of considerable time in the drying rooms.

Another object of the invention is to provide means visual to the operator, for indicating the depth of mold during the charging operation and also the operation of the mold bottom during the entire cycle of the 40 press.

A further object is to provide improved means for regulating the depth of the mold 45 which governs the quantity of clay at each charge.

A further object is to provide mechanism for lowering the charge to the extreme 50 depth of mold before the pressing mechanism begins to function, and furthermore it is an object of this invention to provide improved means for operating the charger.

The invention is illustrated in the accompanying drawings in which—

Fig. 1 is a front elevation; 55

Fig. 2 is a side elevation;

Fig. 3 is a sectional side elevation of the device;

Fig. 4 is a sectional view of the mold box on line 4—4 of Fig. 2; 60

Fig. 5 is a perspective view of the press- 65

ing frame;

Fig. 6 is a detail of the charger operating mechanism;

Figs. 7 and 8 are sectional elevations of 70

modified plungers.

In the drawings numerals 10 and 11 des- 75

ignate the side frames spaced apart by

transverse members 12 and 13 at the bot- 80

tom and plate 14 at the extreme top.

A driving shaft 15 is journaled in bear- 75

ings as 16 on rear of frames 10 and 11 and

an outboard bearing 17 supported on a

small base 18 projecting laterally from and

bolted to frame 11. On driving shaft 15 85

adjacent bearing 17 is mounted a friction

clutch driving pulley 19 adapted to be

thrown in or out of frictional engagement

with driving shaft 15 by the manual rota- 90

tion of hand wheel 20 mounted on pedestal

21 on the delivery floor 22.

A crank shaft 23 journaled in bearings 24 on frames 10 and 11 is rotated from driv- 85

ing shaft 15 by means of gear 25 keyed

thereto and meshing with pinion 25^a se- 90

cured to intermediate shaft 26 operative in

bearings 27, on frames 10 and 11. Inter- 95

mediate shaft 26 is rotated through gear 28,

secured thereto and meshing with a pinion

29 keyed to the driving shaft. 100

A mold box generally designated by 105

numeral 30 consists of a pair of beams 31

and 32, the ends of which fit into recesses

33 and 34 of frames 10 and 11. End blocks

35 and 36 fitting into and slidably in recesses 105

37 and 38 in beams 31 and 32, and suitable

liners as side liners 39 and 40 fitting into

recesses 37 and 38, and end liners 41 and

42 fitting into recesses 43 and 44 in the end

blocks 35 and 36 are all rigidly secured in

assembled relation by bolts 45 passing

through the beams and set screws 45^a

threaded into the frames and abutting the

end blocks. A plurality of cap screws 46

threaded into the ends of beams 31 and 32 serve to resist the thrust of set screws 45^a and further secure the beams against longitudinal movement in recesses 33 and 34.

5 As a convenience in charging or renewing liners a cap screw 47 threaded into end blocks 35 and 36 serves to widen the mold cavity between the end blocks, and screws 47^a threaded into beam 31 and abutting the 10 end blocks serve to widen the mold cavity between the beams 31 and 32.

15 A pressing mechanism comprises a frame generally designated by numeral 48 consisting of a pair of bars 49 and 50 cross connected together by beams 51 and 52 at the top and bottom. The side bars 49 and 50 are each provided with a slot 53 for accommodating a projection 54 on the end blocks 35 and 36 and also for the abutting set 20 screw 45^a.

The side bars 49 and 50 operate vertically in guides 55 on the frame which is provided with take up gibs 56 above the mold box and gibs 57 below the mold box.

25 Upper and lower crossheads 58 and 59 transversely disposed and located between the mold box 30 and beam 52 are movable vertically, being guided in ways 60 located between the side bars 49 and 50 and gibs 57. A toggle 61 is pivotally connected to the crossheads by pins 62 and 63 secured in position by caps 64 and 65 on the upper and lower crossheads respectively. A central toggle shaft 66 pivotally secures the two 35 legs of the toggle together.

As the toggle has to resist very heavy compressive pressures, all the joints are provided with large secondary bearings as indicated by numeral 67 at the crossheads and 40 68 at the central joint.

A rod 69 connects the central toggle shaft 66 with the crank pin 70 of crank shaft 23.

The upper and lower plungers as 71 and 72 are made to conform to the horizontal 45 contour of the mold and commonly consist of die plates 73 and 74 which closely fit the mold, and connecting blocks 75 and 76.

The upper plunger 71 is rigidly secured to the upper beam 51 in alignment with the mold while the lower plunger 72 is rigidly secured to the upper crosshead 58. The lower plunger must be of such length as to extend entirely through the mold and when the upper crosshead engages a stop 55 730 on its downward movement the mold is of maximum depth. At this position the die plate 74 is just within the lower opening of the mold.

60 The frame is raised at determined intervals through the medium of a cam 750 secured to crank shaft 23 acting on a double rocking lever 760 secured to a shaft 77 pivoted in bearings 78 located in frames 10 and 11. A pair of links 79 form an operative 65 connection between the frame 48 and the

forward ends of lever 760 and a roller 80 mounted on the rear end forms suitable engagement with cam 750.

Suitable shoots as 81 deliver clay to a feed hopper 82 located over a charger 83, and secured from horizontal movement by a pair of plates 84 bolted to the frames 10 and 11.

Clay passes from the feed hopper 82 into the charger cavity 85 from which it is delivered to the mold during a reciprocating movement of the charger which is accomplished by the following mechanism:

A pair of racks 86, pivoted to the charger 83 at 87 mesh with gears 88 secured to shaft 89 which is rotatable in bearings 90 and 91 fastened to the charger apron 92.

90 Shaft 89 is rotated by chain and sprocket connection to a counter-shaft 94 provided with bearings 95 fixed to charger apron support 93, a pinion 96 on the latter shaft meshes with a gear segment 96^a secured to a rocker arm 97 pivoted to frames 10 and 11 at 98. Arm 97 is given an oscillatory movement by means of a cam 99 secured to gear 25, engaging a roller 100 connected on arm 97 by pin 101. Chargers of the type shown for conveying clay to the molds of brick presses are old but they are usually operated by connecting rods directly connected to rocker arms and as the operating forces are not all in line with the movement of the charger, uneven wear results.

95 Clays have different characteristics. Some require more pressure than others, over-pressing may cause checking or cracking, barometric changes alter the degree of moisture, ununiform processing of the clay, etc., all make it necessary to provide means manually controlled for altering the quantity of charge, and to this end the following 100 mechanism is provided:

A sleeve 102 provided with integral arms 103 and 104, is pivoted on a shaft 105, secured in bearings 105^a to frames 10 and 11; a rod 106 pivoted to arm 103 at 106^a carries a roller 107 at its lower end and depends from arm 103 directly above the lever 760, a stop 108 limits the downward movement of bar 106.

Rod 106 is connected by a link 109 to a 115 lever 110 pivoted at 111 in frame 10 and rotatively secured to a worm gear segment 112, which is engaged by a worm 113 secured to a shaft 114 provided with suitable bearings on the side of frame 10. A transverse shaft 115 secured in bearings 116 bolted to frames 10 and 11 is geared to shaft 114 by bevel gears 117. A chain and sprocket gearing 118 connects the hand wheels 119 on both sides of the press located conveniently 125 for the operator. By turning the hand wheels 119 the rod 106 is swung closer to or from the pivot shaft 77 of lever 760. The action of the latter mechanism will be further explained in the operation of the press. 130

It is important that the operator should know at any time the quantity of clay being fed at each charge.

In pressing brick a great deal depends on the judgment of the operator as to the quality of the brick as it is pressed, and as before stated, changes in the processing of the clays before charging necessitate changes in the quantity of charge. Sometimes slight changes in the quantity of moisture in the clay require a change in the depth of mold while charging, therefore any instrument that will aid the judgment of the operator is of importance and to this end the following mechanism is provided for showing the location of the lower plunger or mold bottom at any period during the cycle of the press.

A cam comprising an inclined plane 120, secured to the upper crosshead 58, to which the lower plunger is attached, is engaged by a lever 121 pivoted in frame 11 and cross connected by a shaft 122 to a lever 123. A spring 124 serves to hold lever 121 against the plane 120 and a rod 125 serves to transmit motion to a pointer 126 pivoted to the side frame 11 of the press. A scale so arranged with relation to the pointer as to designate the depth of the plunger in the mold is shown at 127.

The operation of the press is as follows: Assuming the lower plunger has moved flush with the top of the mold ejecting a brick therefrom, the charger will move forward under the influence of cam 99, pushing the brick off the plunger onto the delivery apron 128. When the front of charger 83 has passed over the mold the plunger 72 begins to recede under the influence of the flexing toggle 61 and continues to recede until intercepted by the engagement of caps 64 on the upper crosshead with arms 103 and 104 which have before been moved up under the influence of lever 760. Slightly after the recession of the lower plunger 72, the charger 83 will complete its return movement the mold having been filled with clay from the charger cavity 85 during the recession of the lower plunger.

The frame 48 which has been held by cam 750 in its extreme upward position during the functioning of the charger drops by gravity, allowing arms 103 and 104 to recede and allowing the upper crosshead to drop by gravity until intercepted by a permanent stop 730. The charge now is drawn to maximum depth. The upper plunger 71 is now in the mold compressing the clay by the gravity of the parts to which it is rigidly secured; the toggles are straightening under the influence of the crank shaft 23 and the entire pressing mechanism is moved upward under the influence of cam 750 while the plungers are moving towards each other until the straightening of the toggle is completed.

When the upper plunger reaches a point near the top of the mold, the pressure on the brick is released by a slight flex of the toggle 61, and the raising of the pressing mechanism continuing, ejects the brick from the mold and the cycle is completed.

It will be further noted that the lower plunger is held flush with the top of the mold for a period during the initial flex of the toggle and the initial movement of the charger by a spring 129 acting between the beams 52 and lower crosshead 59. An abutment 130 on the mold box engaging the upper crosshead 58 prevents the lower plunger from being urged beyond the mouth of the mold.

Fig. 7 shows a plunger that may be used to advantage on clays of low viscosity. The plunger consists of an outer shell 131 and an inner shell 132 urged outwardly by a spring 133. In the operation of this plunger the inner shell first engages the clay, compressing the center until the resistance of the spring is overcome to bring the pressing surfaces of the two shells flush.

A reversal of construction as shown in Fig. 8 will first engage the clay near the walls of the mold.

I claim as my invention:

1. The combination in a press having a mold, a movable bottom in the mold and means for indicating the depth of the mold at any interval during the cycle of the press.

2. The combination in a press having a mold or pocket within which material is pressed, of a movable bottom in the mold and means movable simultaneously with said bottom for indicating the location of the bottom during the interval of charging.

3. In a press, a mold or pocket within which material is adapted to be pressed, means for charging the mold, and means for automatically indicating any change in the density of the pressed material.

4. The combination in a press having a mold, of mechanism for pressing material in said mold and means operable by said mechanism for indicating any change in the density of the material pressed.

5. The combination in a press having a mold, of mechanism for pressing material in said mold means moving in unison with the bottom of the mold for indicating the location of said bottom at any period during the cycle of said pressing mechanism.

6. In a press, a pressing mechanism comprising a rectangular frame consisting of side bars and cross connecting beams at the top and bottom ends, a mold disposed between the beams, a plunger rigidly secured to the upper beam in alignment with the mold, upper and lower crossheads slidable longitudinally of the side bars, a toggle pivotally secured to and between the crossheads, a lower plunger rigidly secured to the

upper crosshead and forming a bottom for said mold, means for charging the mold, means for flexing and straightening the toggle and means for raising and lowering the frame.

7. In a press, a mold, mechanism including an upper pressing head and a toggle floating relatively to said head for pressing material in the mold, a mold bottom secured

10 to the floating toggle, means for elevating the mold bottom flush with the top of the mold, and means for holding the bottom in this position while the toggle is being flexed.

8. The combination in a press having a mold, mechanism comprising a floating toggle for pressing material in the mold, a mold bottom secured to the floating toggle, means for elevating the mold bottom flush with the top of the mold and a spring located below 20 the toggle for holding the bottom in this position while the pressed material is shifted.

9. The combination in a press, mechanism comprising a rectangular frame consisting 25 of side bars and cross connecting beams at the top and bottom ends, a mold disposed between the beams, an upper plunger rigidly secured to the upper beam in alignment with the mold, upper and lower crossheads slide- 30 able longitudinally of the side bars, a toggle pivotally secured to and between the crossheads, a lower plunger rigidly secured to the upper crosshead and forming a bottom for said mold, means for raising and lowering 35 the frame and means for receding the lower plunger while the frame is at maximum elevation.

10. The combination in a press, mechanism comprising a rectangular frame consisting 40 of side bars and cross connecting beams at the top and bottom ends, a mold disposed between the beams, an upper plunger rigidly secured to the upper beam in alignment with the mold, upper and 45 lower crossheads slideable longitudinally of the side bars, a toggle pivotally secured to and between the crossheads, a lower plunger rigidly secured to the upper crosshead and forming a bottom for said mold, means for raising and lowering the frame 50 and means for receding the lower plunger while the frame is at maximum elevation, and means for intercepting the recession 55 when a predetermined depth of mold has been reached.

11. The combination in a press, mechanism comprising a rectangular frame consisting 60 of side bars and cross connecting beams at the top and bottom ends, a mold disposed between the beams, an upper plunger rigidly secured to the upper beam in alignment with the mold, upper and lower crossheads slide- 65 able longitudinally of the side bars, a toggle pivotally secured to and between the crossheads, a lower plunger rigidly secured to the

upper crosshead and forming a bottom for said mold, means for raising and lowering the frame and means for receding the lower plunger while the frame is at maximum elevation, means for intercepting the recession 70 when a predetermined depth of mold has been reached, and means for releasing said intercepting means upon the lowering of the frame.

12. The combination in a press, mechanism 75 comprising a rectangular frame consisting of side bars and cross connecting beams at the top and bottom ends, a mold disposed between the beams, an upper plunger rigidly secured to the upper beam in alignment with the mold, upper and lower crossheads slide- 80 able longitudinally of the side bars, a toggle pivotally secured to and between the crossheads, a lower plunger rigidly secured to the upper crosshead and forming a bottom for 85 said mold, means for raising and lowering the frame and means for receding the lower plunger while the frame is at maximum elevation, means for intercepting the recession when a predetermined depth of mold has 90 been reached, means for releasing said intercepting means upon the lowering of the frame, and means for stopping the recession at maximum depth of mold.

13. The combination in a press having a 95 mold, a plunger forming the bottom of the mold, means for adjusting the depth of the mold, means for charging the mold level with its top, an upper plunger adapted to enter the mold and means for lowering the charge to the maximum depth of the mold before the upper plunger enters.

14. The combination in a press having a mold, mechanism for pressing material in the mold, means for adjusting the depth of the mold, means for charging the mold and means for lowering the charge to the maximum depth of mold before the beginning of the pressing operation.

15. In a press the combination with a 110 mold, a lower plunger movable vertically therethrough and an upper plunger adapted to co-act with said lower plunger of an adjustable member adapted to stop the downward movement of the lower plunger while the upper plunger is inactive and automatic means for removing said stopping member when the upper plunger becomes active.

16. In a brick press provided with a mold, means for charging said mold, an upper and a lower plunger associated with said mold, means for operating said plungers, said means comprising a toggle pivotally connected to said lower plunger means including a link for operating said toggle and means independent of said link for elevating said upper plunger and for holding said upper plunger stationary during the charging operation.

17. The combination in a press having 120

- 5 a mold, an upper and lower plunger adapted to co-act with the mold, means for charging the mold when the upper plunger is non-active and means for lowering both plungers immediately after charging. 18. The combination in a press having a mold, an upper and lower plunger adapted to co-act in the mold, means for charging the mold when the upper plunger is non-active, means for lowering both plungers immediately after charging and means for arresting the movement of the lower plunger when the mold is of maximum depth. 19. In a press the combination with a mold having a mold bottom movable vertically therethrough of an adjustable member adapted to stop the downward movement of the bottom, charging means, pressing mechanism, and means for removing the stopping member before the pressing mechanism begins to function. 20. In a press, the combination with a mold having a plunger movable vertically therethrough of an adjustable member adapted to arrest the movement of the plunger on its downward movement in the mold and means for mechanically releasing the adjusting member after certain elements have functioned. 21. The combination in a press having a vertical rectangular frame comprising vertical side bars, and beams connecting the side bars at both ends of an upper and lower crosshead slidable longitudinally of the side bars, a toggle disposed between the crossheads and pivoted thereto and a spring located between the lower crosshead and the adjacent frame beam. 22. The combination in a press having a frame comprising side bars and beams rigidly connecting the side bars at both ends of a pair of crossheads slidable longitudinally of the side bars and a toggle disposed between the crossheads and pivoted thereto. 23. The combination in a press having a rectangular frame comprising side bars and beams rigidly connecting the side bars at both ends of a pair of crossheads slidable longitudinally of the side bars, a toggle disposed between the crossheads and pivoted thereto, means for flexing the toggles and means for holding either of the crossheads in any desired position with relation to the frame. 24. The combination in a press having a rectangular frame comprising side bars and beams rigidly connecting the side bars at both ends of a toggle slidably connected to the side bars and between the beams, means for flexing and straightening the toggle and means for moving the toggle to any desired position between the frame beams. 25. In a press for pressing material into form, having a mold, a depth of mold adjusting device consisting of a manually controlled stop in the path of the mold bottom and automatic means for removing said stop at a determined point in the cycle of the press. 26. In a brick press in combination a mold, means for charging the mold, a plunger adapted to recede during the charging operation and means manually adjustable and mechanically operated for intercepting said recession. 27. The combination in a brick press having a mold, upper and lower plungers operative in the mold, means for moving the plungers toward each other to predetermined distance apart and means incorporated in the plungers for pressing material in the mold successively at various points and finally to form a brick of uniform thickness. 28. The combination in a brick press having a mold, upper and lower plungers operative in the mold, means for moving the plungers toward each other to a predetermined distance, a part of the pressing face of one said plunger having yielding engagement with material being pressed in the mold. 29. In a brick press a plunger adapted for pressing material in a mold comprising in combination a rigid pressing face and a yielding pressing face and means for yielding holding said yielding pressing face in advance of said rigid pressing face during the initial pressing of said material. 30. In a brick press, a plunger adapted to press material in a mold, comprising in combination, a rigid pressing face and a yielding pressing face the yield of the latter ceasing when the entire pressing face is flush. 31. In a brick press, a plunger adapted to press material in a mold, comprising in combination a rigid element having a pressing face and a spring pressed element having a pressing face normally beyond the rigid face and adapted to recede flush with the rigid face before the final pressure on the material being pressed has been reached. 32. In a brick press provided with a mold, means for charging said mold, a pair of plungers associated with said mold, means for operating said plungers, said means comprising a toggle for operating one of said plungers, means including a crank operated link for operating said toggle and means independent of said link for elevating said upper plunger and for holding the same elevated during the charging operation. 33. In a press having a mold, an upper and a lower plunger for pressing material in said mold, means including a toggle for operating said lower plunger, means for ele- 70 75 80 85 90 95 100 105 110 115 120 125 130

vating said lower plunger and means for holding said upper plunger stationary, and for holding said lower plunger in maximum elevated position during the initial flexing of said toggle.

34. In a press having a mold, an upper and a lower plunger for pressing material in said mold, means including a toggle for operating said lower plunger, means for elevating said lower plunger and means engaging said toggle for maintaining said lower plunger in maximum elevated position during the initial flexing of said toggle.

35. The combination in a press having a

mold, a plunger forming the bottom of the mold, means for adjusting the depth of the mold, means for charging the mold level with its top, an upper plunger adapted to enter the mold, and means for lowering the charge before the upper plunger enters said mold.

36. In a brick press, a mold, a plunger adapted to press material in said mold, said plunger comprising a rigid face and a relatively movable face, and means for causing said movable face to engage said material in advance of the rigid face during the initial pressing of the material in said mold.

WALTER H. COTTON.
